[57] CLAIM

The ornamental design for a kiosk, as shown and de-
scribed.

DESCRIPTION

FIG. 1 is a perspective view of a kiosk showing my new
design;

FIG. 2 is a side elevation thereof; and

FIG. 3 is a top plan view thereof.

The bottom of the table and showcases is flat and unor-
namental and the underside of the canopy is conven-
tional.

FIG-1

FIG-2

FIG-3
